SHIPPING AND/OR STORING RECEPTACLE

Walter Kline, Wellington, and William A. Brubaker, Akron, Ohio; said Kline assignor to Ethel H. Morrison, Wellington, Ohio

Application October 9, 1934, Serial No. 747,631

11 Claims. (Cl. 220—10)

The present invention relates in general to shipping and/or storing receptacles and has particular reference to a vessel or container for liquids and in which any such material to be shipped or stored is subjected to the sanitary and other desirable conditions which prevail when a glass or other non-corrosive material is used as the shipping or storing receptacle.

One of the important features of the invention resides in the provision of means for protecting a glass or other fragile vessel when in transit or when stored so that the ordinary abuse to which the receptacle is subjected will not injure or otherwise destroy the same.

Another feature of the invention resides in the construction of a glass or other non-corrosive vessel which is adapted to contain materials for storing or shipping purposes and in which the materials are contained within such a vessel in an insulated condition so that changes in temperature will not necessarily affect the qualities of the stored material, at least to the extent that such changes in temperature as may be expected under ordinary shipping and storing conditions will necessarily make a change in the condition of the material. In this connection we are particularly referring to the shipping and storing of beer or other such liquid wherein it is desirable to maintain the liquid at more or less constant temperature between the time it is barreled and dispensed. Aside from the instance related in the invention of the container we also have in mind the provision of a vessel which may be well adapted for use in transporting acid or any other such material which requires the use of a non-metallic container such as glass or other non-corrosive material which is unaffected by contact with certain acids. Due to the fragile qualities of such a container it becomes necessary to protect the same against ordinary handling abuses and it is therefore another object of the invention to construct a shipping and storing vessel in a manner to realize these advantages without increasing the cost of construction to a prohibited extent.

With these and other objects in view, which will be apparent from the following detailed description of the accompanying drawings we will now proceed to describe the construction of the invention with reference to the illustrative embodiment shown in the accompanying drawings.

In said drawings:

Fig. 1 is a view in longitudinal section of a barrel keg or the like which is especially adapted

for the purpose of containing beer or other such liquid;

Fig. 2 is a view in end section of such a barrel;

Fig. 3 is a view in cross section of such a barrel as shown in Fig. 1; and

Fig. 4 is a detailed view of a modification of the barrel shown in Fig. 1.

Referring now to the drawings in detail and with particular reference to the barrel or keg construction shown in Figs. 1 to 4, inclusive, 5 represents an inner container which is formed of glass or other non-corrosive material. In view of the fragile structure of this container it becomes necessary to protect the same and with this end in view we propose to house it within 15 an outer metallic shell 6.

So far as the barrel or keg is concerned we propose to fabricate the outer shell 6 of sheet metal using an asbestos liner 7 in combination with the outer shell. The outer shell being 20 formed of sheet metal may be easily fashioned with corrugated ribs 8 and 9 of different diameters and which extend completely around the circumference of the shell in spaced relation, as best shown in Fig. 1. These ribs are provided for the purpose of strengthening the shell as well as to serve as raised areas upon which the barrel may be rolled and which also act in the capacity of bumpers or buffers to prevent the shell from collapsing when the barrel is 25 dropped on a hard surface as may be expected when the barrel is being handled in transportation or otherwise moved from place to place. It is also to be noted that these raised areas 30 particularly the larger ribs 8 are offset outwardly relatively to the bung or filling opening in the side of the barrel. In this way the bung or filling opening is thus protected against injury. The ends of the barrel are likewise equipped to 35 withstand shocks by means of a circular hollow rim 10. Both ends of the barrel being thus equipped with this rim add rigidity to the barrel ends and enables the same to withstand the 40 more or less rough handling and also offers an 45 end structure which enables the barrel to be conveniently handled on end, so to speak. These ribs 10 are welded or otherwise joined to the end discs 11 of the barrel with the outer 50 circular periphery of the end discs 11 fashioned to embrace the rims 10 as shown in Fig. 1. The sides or cylindrical section of the barrel is made with end portions which overlie the outwardly turned peripheries of the discs 11 and with the 55

discs 11 are welded or otherwise fixed to the ribs 10.

Since a bung is arranged for one end of the barrel the construction of the discs 11 at one end of the barrel is modified to accommodate the bung. However, so far as concerns the disc at the opposite end of the barrel attention is called to the fact that it is a continuous plate having a central offset portion 12 with a stepped 5 diameter as at 13 to accommodate the circular rubber cushion 14 which supports and cushions the receptacle 5. The opposite disc 11 is substantially the same except that the offset portion or area 12 is made with a central opening 10 to accommodate the bung.

In order to suspend or support the inner non-corrosive receptacle 5 so as to avoid injury or destruction of the same we propose to employ, in addition to the rubber end cushions 14, a 15 centrally disposed cushion 15 which may be constructed of rubber or other suitable resilient material. This central cushion 15 as best shown in Fig. 3 will extend around the outer circumference of the inner receptacle 5 with its ends 20 terminating in opposed relation at the side bung or filling opening.

The end cushions 14 which are rings are confined on seats made by the steps in the end discs 11 and embrace outwardly offset shoulders 25 16 which are fashioned on the ends of the inner receptacle 5. In this way the cushions 14 are confined in position to support the more or less fragile inner receptacle and as thus supported 30 in cooperation with the center cushion 15 shocks under which the barrel is subjected will be absorbed to the extent of avoiding injury 35 to the receptacle 5.

In addition to these shock absorbing features as realized by the cushions 14 and 15 we 40 also enclose the receptacle 5 with a plastic covering 17. In practice we have found that this plastic covering can best be realized when we employ a bituminous or like composition. In 45 selecting this material we have in mind the insulating qualities which may be realized as well as the shock absorbing qualities of such a material. An asphalt composition which may well serve this purpose may be realized by a mixture 50 of asphaltum with a certain amount of latex and rosin added in proportions which will maintain the desired plastic qualities with a consistency thick enough to prevent the same from flowing under ordinary temperatures after the 55 receptacle has been thus coated. The receptacle being coated with this composition is not only protected against shock but suitably insulated as well, so that the contents of the container is insulated against temperature changes which 60 is desirable in handling beer and other more or less perishable liquids. That is to say, liquids which are apt to have their qualities changed by temperature variations.

As a further means of protecting the inner 65 container 5 as well as to retain the bituminous coating 17 we cover the coating with a snug fitting jacket 17' of sheet material, preferably sheet metal. This jacket may be fabricated in sections, or in any other manner suitable for 70 the purpose, the idea being to enclose as much of the container as possible, taking into account the openings made necessary by the bung fittings and resilient supports for the container.

To further insulate the receptacle 5 we also 75 propose to employ a material for the liner 7

which is known for its insulating properties such for instance as asbestos. This liner 7 is made to approximately conform to the sides of the barrel with end portions in the form of discs having central openings which engage the end 5 cushions 14 with their outer peripheries joining with the side portions of the liner. The ends of the side portions of the liner bear against the end discs 11 and the liner is, of course, made in divided sections to accommodate the central 10 cushion 15 and the side bung structure. When thus constructed it will be seen that a dead air space is left between the coated outer surface of the receptacle 5 and the liner 7. While the air is not evacuated from this space to leave a 15 vacuum the space does serve as an added insulation and cooperates with the liner and the coating 17 to add to the insulated qualities of the arrangement.

Referring now to the bung or filling openings 20 we have shown such an arrangement in both the side and end of the barrel. We have shown the bung in the side and the end in the present showing to illustrate how it would be possible to provide for the bung in either location or in both 25 locations if desirable. In providing for the side bung we propose to fashion the inner receptacle 5 with an increase in its thickness as at 18. This increase in thickness is formed in the area immediately surrounding the opening. The inner walls 30 of this opening being of considerable depth due to the increase in thickness 18 are rounded off as shown to accommodate a relatively thick gasket 19 made of rubber or other more or less readily pliable material. This gasket 19 is made with 35 an annular depression around the same to fit the opening in the receptacle 5 and in order to make a tight closure as well as to provide for a bung opening we propose to employ a valve like disc 20 which is seated on the inside of the gasket 19 40 having an upstanding interiorly threaded sleeve to receive the headed bolt like plug 21. The head of the bolt like plug 21 bears against a metallic cup 22 which is seated in the hollow portion of the gasket 19. By using a spanner wrench, for 45 which the head of the bolt 21 is especially fitted, the bolt may be turned to draw the disc 20 and the cup against the inside and outside of the gasket causing the same to wedge itself tightly in the bung opening and make a perfectly tight 50 closure. In this connection attention is called to the overlapping portions of the receptacle around the inside and outside of the opening.

In addition to this bung construction we also 55 employ a ring 23 to reinforce the opening. The flange of the ring 23 is made with a slot to receive the outer shell 6 and the depending flange on the ring is dovetailed in the annular undercut slot in the thickness 18 around the bung opening. The ring 23 encircles the outer portion 60 of the gasket 19 and thus protects the same as well as protecting the thickness 18 of the inner receptacle around the bung opening. The inner liner 7 bears against the depending flange on the ring 23 and rests upon the shoulder on 65 the thickness 18 in which the flange is dovetailed.

The construction of the end bung is modified to the extent that a different type of closure is employed. A gasket 24 is utilized which corresponds substantially to the gasket 19. However, instead of employing the ring 23 the end disc 11 is seated in an annular slot in the gasket. A sleeve 25 is fitted in the gasket having a flange 26 on the outside and a threaded inner end 27. 75

Threaded on the end 21 is another inner end 28 which is made with flange 29 bearing against the gasket and a center projection 30 having a bore for the reception of a stopper such as a plug. The internal head 31 of the center projection 30 is made to accommodate a special wrench such as a spanner which engages the notches 32 (see Fig. 2). The flange 26 is also fitted with openings 33 to accommodate a wrench so that the nut 28 may be held and the sleeve 25 turned or vice versa which will develop a wedging effect to cause the gasket 24 to tightly impinge in the opening made to receive it and thus make a proper closure. A washer 34 may be employed on the outside of the gasket under the flange 26. It will thus be seen that either arrangement of bung fitting may directly engage with the inner receptacle without injuring the receptacle and at the same time provide a perfectly tight fit to prevent leakage.

In Fig. 4 we have shown how it is possible to use pneumatic protectors on the inside of the ribs 8. Each of these pneumatic protectors may be equipped with valves 35 for inflating the same with air. The space between the bottom and the shell will be filled with the asphalt composition as clearly indicated.

Any suitable closure for the mouth of the carboy may be used. Since this is the case we have not considered it necessary to illustrate any particular type.

Where we have used the words "glass" or "non-corrosive" as a descriptive term for explaining the nature and physical properties of the inner container 5 it should be understood that we have in mind using not only glass but also pottery or other ceramic materials, enamel ware or even stainless steel. It is therefore pointed out that when we speak of "non-corrosive" material in the description and claims we wish the same to be interpreted as any material suitable for the purpose having the qualities described.

By way of further explanation we wish it to be made clear that we consider it of importance under some conditions of use to take advantage of the resilient properties of the pneumatic protectors or buffers shown in Fig. 4. As another means of realizing these resilient advantages we can apply a rubber covering 8' upon the ribs 8 and also apply a rubber ring around the edge of the barrel ends. By making these rubber coverings of ample thickness a rubber tire effect may be accomplished which will absorb shock in handling the barrel and also provide spaced restricted rubber areas around the central portion of the barrel and the ends thereof upon which it may be rolled.

Having thus described an embodiment of our invention what we claim and wish to secure by Letters Patent of the United States is:

1. In a receptacle of the character described, an outer protective shell, an inner non-corrosive container housed within said shell, resilient cushioning means supporting the container within the shell, a bituminous covering for said container and a jacket of sheet material snugly fitting over said bituminous covering.

2. In a receptacle of the character described, an outer protective shell, an inner non-corrosive container, resilient cushioning means supporting the container within the shell and in spaced relation thereto, a bituminous covering for the

container in the space between the shell and container and a sheet metal jacket snugly fitting over said bituminous covering.

3. In a receptacle of the character described, an outer protective shell said shell being provided with shock absorbing means located in offset relation to the surface of the shell, an inner container resiliently supported within said shell, a protective covering of bituminous material for said container and a protective jacket snugly fitting over said bituminous covering.

4. A barrel or the like receptacle, comprising an outer metallic shell fashioned with separately formed sides and end portions joined and reinforced at their meeting edges, an inner non-corrosive container, cushioning means supporting the inner container within the outer shell in spaced relation thereto, a covering of bituminous material for the inner container, a protective jacket snugly fitting over said bituminous covering and a liner within the space between the outer shell and the inner container.

5. The combination as set forth in claim 4 and in which the inner container is provided with a filling opening and in which the filling opening is equipped with a resilient fitting joining the shell with the container at the filling opening.

6. In a spaced wall receptacle, an outer shell, an inner container therein, resilient members cushioning the inner container within the shell, cooperating supports on the container and shell for holding said resilient members in position, a bituminous covering for the container and a protective jacket snugly fitting over said bituminous covering.

7. A spaced wall receptacle as claimed in claim 6, further characterized by a filling opening for the inner container which extends through the outer shell and with a resilient fitting for said opening joining the outer shell with the inner container at said opening.

8. In a receptacle of the character described, an outer reinforced metallic shell, an inner container resiliently supported in said shell and insulated therefrom, said container having a filling opening extending through the shell, a deformable gasket for said opening and means co-operating with the gasket for causing the same to engage within the filling opening to seal the same.

9. In a receptacle of the character described, an outer metallic shell fashioned with sides and separately formed ends, elevations on the shell reinforcing the same, hollow circular rims reinforcing the shell at the ends thereof, said rims and separately formed ends for the shell being joined to the side of the shell with an overlapping joint, an inner container resiliently supported within the shell, a bituminous jacket for said container and other means between the shell and container and cooperating with the bituminous jacket for insulating the container.

10. The combination as set forth in claim 9, and in which some of the elevations on the shell are equipped with pneumatic tubes to serve as shock absorbers for the receptacle.

11. The combination as set forth in claim 9 and in which some of the elevations on the shell are equipped with rubber treads substantially as and for the purpose described.

WALTER KLINE.
WILLIAM A. BRUBAKER.
